Anderson Co., a corporation of Rhode Island

Filed June 5, 1963, Ser. No. 75,233

Term of patent 14 years

(Cl. D7—6)

FIG. 1

FIG. 3

FIG. 1 is a perspective view of a shoe buckle showing my new design as it appears on a shoe, the broken line showing of a shoe being for purposes of illustration only;

FIG. 2 is an enlarged front view of the shoe buckle; and,

FIG. 3 is an enlarged end view thereof taken from the lefthand side of FIG. 2, the broken line fragmentary showing of the shoe being for purposes of illustration only.

I claim:

The ornamental design for a shoe buckle, substantially as shown and described.
